UNITED STATES PATENT OFFICE.

HENRY GOLDTHORP, OF PHILADELPHIA, PENNSYLVANIA, ASSIGNOR TO
E. H. GODSHALK, OF SAME PLACE.

DESIGN FOR FRINGE.

SPECIFICATION forming part of Design No. 13,509, dated January 2, 1883.

Application filed October 30, 1882. Term of patent 3½ years.

To all whom it may concern:

Be it known that I, HENRY GOLDTHORP, a citizen of the United States, residing in the city and county of Philadelphia, State of Pennsylvania, have invented and produced a new and original Design for Fringe, of which the following is a specification, reference being had to the accompanying photographic illustration, forming part thereof.

10 My design consists of pendants of conical or tapering form, inverted or having the bases or widest parts above, the surfaces of the pendants being spirally fluted.

15 It also consists of pendants of conical or tapering form, inverted or having their bases or widest parts above, and ornamented at their ends with balls or swells, the surfaces of the pendants being spirally fluted.

20 A represents pendants, which, connected with a suitable head, are of conical or taper-

ing form, inverted or having their bases or widest parts above, the surfaces of the pendants being spirally fluted.

B represents balls, which ornament the pendants at one or both ends thereof.

25

I claim—

1. The design for fringe having pendants of conical or tapering form, the bases or widest parts being above, the surfaces of the pendants being spirally fluted, substantially as above 30 shown and described.

2. The design for fringe having pendants of conical or tapering form, the bases or widest parts being above, with fluted surfaces and end balls, substantially as above shown and 35 described.

HENRY GOLDTHORP.
